[57] CLAIM

The ornamental design for a bowling ball caddy, substantially as shown and described.

DESCRIPTION

FIG. 1 is a top plan view of a bowling ball caddy showing my new design;

FIG. 2 is a left side elevational view;

FIG. 3 is a front elevational view;

FIG. 4 is a right side elevational view;

FIG. 5 is a bottom plan view; and

FIG. 6 is a top plan view thereof with the cover in an open position.
